BOAT HULL

Donald M. Smith, 9001 Imperial Ave.,
Garden Grove, Calif.

Filed Apr. 20, 1959, Ser. No. 55,582

Term of patent 14 years

(Cl. D71—1)

FIG. 1.

FIG. 2.

FIG. 3.

FIG. 4.

FIGURE 1 is a bottom plan view of a boat hull showing my new design.

FIGURE 2 is a side elevation thereof, the opposite side being substantially the same in appearance.

FIGURE 3 is a top plan view thereof.

FIGURE 4 is a front elevation thereof.

I claim:

The ornamental design for a boat hull, substantially as shown and described.
